ARM CONSTRUCTION FOR ROUTERS

Theodore C. Mann, Beloit, Wis., assignor to Ekstrom-Carlson & Co., Rockford, Ill., a corporation of Illinois

Application July 18, 1957, Serial No. 672,720

6 Claims. (Cl. 144—136)

This invention relates to routers and, more particularly, to double arm routers in which an inner arm is pivotally connected at one end to a base to swing about a first vertical axis and an outer arm is pivotally connected at one end to the free end of the inner arm to swing about a second vertical axis. In such routers, a spindle for a cutting tool is supported on the free end of the outer arm to turn about a third vertical axis.

The general object of the invention is to provide in a router of the above character a novel means for locating the three axes relative to each other so that all three are exactly parallel and this without requiring extreme accuracy in the construction and assembly of the pivotal connections.

A more detailed object is to divide each arm into two sections which are joined by a horizontal pivot permitting the sections to be turned relative to each other to bring the axes at each end of the arm into parallelism and to clamp the sections in the selected angular position. The invention also resides in the construction and arrangement of the particular means for turning the sections about the pivot and clamping the sections together.

Other objects and advantages of the invention will become apparent from the following detailed description taken in connection with the accompanying drawings, in which—

Figure 1 is a fragmentary elevation of a router embodying the novel arrangement of the present invention, parts being broken away and shown in section.

Fig. 2 is an enlarged sectional view taken along the line 2—2 in Fig. 1.

Fig. 3 is a fragmentary plan view of the router, parts being broken away and shown in section.

Fig. 4 is an enlarged fragmentary sectional view taken along the line 4—4 in Fig. 1.

Fig. 5 is an enlarged sectional view taken along the line 5—5 in Fig. 1.

Fig. 6 is an enlarged fragmentary sectional view taken along the line 6—6 in Fig. 2.

As shown in the drawings for purposes of illustration, the invention is embodied in a double arm router comprising an elongated horizontal inner arm 10 pivotally mounted at one end on a base 11 to swing about a vertical axis *a* and pivotally connected at the other end to an elongated outer arm 12 whereby the outer arm may swing relative to the inner arm about a second vertical axis *b*. A cutting tool 13 is supported on the spindle of a motor 14 to rotate about a third vertical axis *c* and the motor slides up and down in ways 15 (Fig. 3) on the free end of the outer arm. Such sliding is effected by a hydraulic piston and cylinder type motor 16 which is mounted on the outer arm and is connected to the motor 14 through a bar 17 (Fig. 1). When the cutter 13 is lowered, it projects through a bushing 18 which is on a bracket 19 projecting forwardly from a vertical slide 20. The latter is adjustable in ways 21 (Fig. 3) by a screw 22 so that the bushing may be set at selected heights.

To form the pivotal mounting of the inner arm 10, a

2

post 23 projects up vertically from the base 11 along the axis *a* with its upper end received in the overhanging arm 24 of a column 25 bolted to and upstanding from the base. The inner end of the arm 10 surrounds the post and is journaled thereon by means of anti-friction bearings 26. At its outer free end, the inner arm is bifurcated to form vertically spaced legs 27 and the inner end of the outer arm projects in between the legs. A vertical shaft 28 extends through the outer arm along the axis *b* and the ends of this shaft project into the legs 27 where they are journaled by conical bearings 29 (see Fig. 4). Axial thrust bearings 30 are disposed between each leg 27 and the outer arm 12 and the legs are drawn tightly against the outer races 31 of these bearings by nuts 32 threaded onto the ends of the shaft 28 to prevent axial shifting of the outer arm during service use.

With the foregoing arrangement, the arms 10 and 12 may be swung about their respective axes *a* and *b* to traverse the cutter 13 around the periphery of a workpiece suitably supported beneath the cutter. Such swinging of the arms may be effected manually and, for this purpose, handles 33 are supported by bars 34 which are projected forwardly from the sides of the outer arm.

According to the present invention, the parts of the router are constructed and arranged in a novel manner so that the axes *a*, *b* and *c* may easily be made to parallel each other precisely without the necessity of extreme accuracy in the formation and assembly of the pivotal joints for the arms 10 and 12. To these ends, the inner arm is formed by sections 35 and 36 and the outer arm by sections 37 and 38 and the two sections of each arm are joined by a connection which permits one section to be turned, relative to the other, about a horizontal axis to bring the axis on one section parallel to the axis on the other section. Each connection comprises a pivot 39 which joins the two arm sections for relative turning and a means for locking the sections in the angular position in which the axes are parallel.

In the present invention, vertical surfaces 40 are machined on the adjacent ends of the sections 37 and 38 of the outer arm 12 and these surfaces abut against each other. A horizontal pin 39 projects into each of the sections at their machined ends and near the top of the arm and is journaled therein to constitute the pivot 39 of the connection between the sections. Thus, the pin 39 defines a horizontal axis *d* about which the section 38 may be turned relative to the section 37.

The means for adjusting the angular position of the arm section 38 relative to the section 37 includes a second pin 41 which is spaced below and parallels the pin 39. One end of the pin 41 is received snugly in a hole 42 in the machined end of the section 37 while the other end of the pin projects into a laterally enlarged hole 43 (see Fig. 2) in the abutting end of the section 38. The enlargement of the hole 43 permits limited swinging of the section 38 about the axis *d*. Such swinging is effected herein by two screws 44 which are threaded into opposite sides of the arm section 38 and abut against the sides of the pin 41.

By backing off one screw 44 and tightening the other, the section 38 may be turned about the axis *d* until the axis *c* is parallel to the axis *b*. The two sections 37 and 38 are clamped together in the adjusted position by bolts 45 which project through holes 46 (Fig. 6) in the section 37 and are threaded into the section 38, the holes 46 being enlarged to permit the relative turning of the sections to bring the axes *b* and *c* into parallelism. A similar connection joins the sections 35 and 36 of the inner arm 10, the corresponding parts of this connection being indicated by the same but primed reference characters.

It will be observed that the axes *a*, *b* and *c* may be made to parallel each other simply by loosening the bolts

45 and 45' and adjusting the screws 44 and 44'. There need be no extreme accuracy in journaling the arms 10 and 12 in the bearings 26, 29 and 30. With the present invention, it has been possible to align the axes so accurately as to have the cutter 13 maintain tolerances of several thousandths of an inch even though the arms 10 and 12 are four or five feet long. Moreover, the invention permits the bearings 30 to be clamped tightly in place to practically eliminate end play of the shaft 28 and thus maintain the accurate location of the axis c relative to the axis b.

I claim as my invention:

1. In a router, the combination of, a first horizontal arm section, means supporting said arm section to turn about a first vertical axis disposed adjacent one end of the section, a second horizontal arm section having one end abutting against the free end of said first section, a spindle rotatably supported on the other end of said second section to turn about a second vertical axis, and a connection joining the abutting ends of said sections, said connection comprising a pivot joining said second section to said first section to swing relative to the latter about a horizontal axis, two screws laterally spaced from said pivot and threaded into opposite sides of one of said sections to abut against a part of the other section on opposite sides thereof, whereby threading said screws turns one section relative to the other about said pivot, one of said sections having a plurality of holes extending longitudinally of the section, and a plurality of bolts smaller than said holes projecting through the holes and threaded into the other section to permit one section to be turned relative to the other to locate said axes parallel to each other, said bolts when tightened clamping said sections in a selected angular position.

2. In a router, the combination of, a first horizontal arm section, means supporting said arm section to turn about a first vertical axis disposed adjacent one end of the section, a second horizontal arm section having one end abutting against the free end of said first section, a spindle rotatably supported on the other end of said second section to turn about a second vertical axis, and a connection joining the abutting ends of said sections, said connection comprising a pivot joining said second section to said first section to swing relative to the latter about a horizontal axis, means for turning said second section about said pivot to locate said second axis parallel to said first axis, one of said sections having a plurality of holes extending longitudinally of the section, and a plurality of bolts smaller than said holes projecting through the holes and threaded into the other section to permit said second section to be turned about said pivot, said bolts when tightened clamping said sections in a selected angular position.

3. A router comprising a base, an elongated inner arm pivotally connected at one end to said base to swing about a first vertical axis, an elongated outer arm pivotally connected at one end to the free end of said inner arm to swing relative thereto about a second vertical axis, a spindle rotatably supported on the other end of said outer arm to turn about a third vertical axis, each of said arms being formed by two sections having vertical surfaces abutting against each other, and two connections, one joining the abutting surfaces of the sections of each of said arms, each of said connections comprising a pivot joining the corresponding sections to swing relative to each other about a horizontal axis, two screws laterally spaced from

said pivot and threaded into opposite sides of one of said sections to abut against a part of the other section on opposite sides thereof, whereby threading said screws turns one section relative to the other about said pivot, and means for clamping said sections in a selected angular position.

4. In a router, the combination of, a first horizontal arm section, means supporting said arm section to turn about a first vertical axis disposed adjacent one end of the section, a second horizontal arm section having one end abutting against the free end of said first section, a spindle rotatably supported on the other end of said second section to turn about a second vertical axis, and a connection joining the abutting ends of said sections, said connection comprising a pivot joining said second section to said first section to swing relative to the latter about a horizontal axis, two screws laterally spaced from said pivot and threaded into opposite sides of one of said sections to abut against a part of the other section on opposite sides thereof, whereby threading said screws turns one section relative to the other about said pivot, and means for clamping said sections in a selected angular position.

5. A router comprising a base, an elongated inner arm pivotally connected at one end to said base to swing about a first vertical axis, an elongated outer arm pivotally connected at one end to the free end of said inner arm to swing relative thereto about a second vertical axis, a spindle rotatably supported on the other end of said outer arm to turn about a third vertical axis, each of said arms being formed by two sections having vertical surfaces abutting against each other, and two connections, one joining the abutting surfaces of the sections of each of said arms, each of said connections comprising a pivot joining the corresponding sections to swing relative to each other about a horizontal axis and means for turning said sections relatively about said pivot and clamping the same in a selected angular position, whereby the two sections of each arm may be adjusted relative to each other to make all of said axes parallel to each other.

6. In a router, the combination of, a first horizontal arm section, means supporting said arm section to turn about a first vertical axis disposed adjacent one end of the section, a second horizontal arm section having one end abutting against the free end of said first section, a spindle rotatably supported on the other end of said second section to turn about a second vertical axis, a connection joining the abutting ends of said sections, said connection comprising a pivot joining said second section to said first section to turn relative to the latter about a horizontal axis extending longitudinally of said sections, a threaded member laterally spaced from said pivot and threaded transversely into one of said sections to act against the other section and turn one section relative to the other about said pivot thereby to dispose said second axis exactly parallel to said first axis, and separate means for clamping said sections in a selected angular position.
